COPYING MACHINE

Fritz Blank, Hollywood, Fla., assignor to Copystatics
Manufacturing Corp., Miami Lakes, Fla., a cor-
poration of New York

Filed May 6, 1968, Ser. No. 11,793

Term of patent 14 years

Int. Cl. D18—03

U.S. Cl. D61—1

FIG. 1.

FIG. 2.

FIG. 3.

FIG. 4.

FIG. 5.

FIG. 6.

FIG. 1 is a top plan view of the copying machine;
 FIG. 2 is an elevational view of one side thereof;
 FIG. 3 is an elevational view of the other side thereof;
 FIG. 4 is a front view thereof (as seen from the right side of FIG. 1);

FIG. 5 is a rear view thereof; and

FIG. 6 is a sectional view taken through the line 6—6 of FIG. 5 showing the contour of a portion of the machine.

I claim:

The ornamental design for a copying machine, as shown.
